D15-2. OR D13,616 EX

DESIGN FOR A STEAM-ENGINE.

Design No. 13,616, dated February 13, 1883.

UNITED STATES PATENT OFFICE.

ADAM ROSENKRANZ, OF ALLEGHENY, PENNSYLVANIA.

DESIGN FOR A STEAM-ENGINE.

SPECIFICATION forming part of Design No. 13,616, dated February 13, 1883.

Application filed October 3, 1882. Term of patent 7 years.

To all whom it may concern:

Be it known that I, ADAM ROSENKRANZ, a citizen of the United States, residing at Allegheny, in the county of Allegheny and State of Pennsylvania, have invented and produced a new and original Design for Steam-Engines, of which the following is a full, clear, and exact description.

This design has special reference to the ornamental contour of the main standard and bed-plate or base of steam-engines of the "vertical" type, the object being to promote the general symmetry of the machine as a whole, as hereinafter more particularly described.

Reference is to be had to the accompanying drawings, forming part of this specification, in which similar letters of reference indicate corresponding parts in both the figures.

Figure 1 is a front perspective view of my newly-designed engine, and Fig. 2 is a perspective view thereof at the fly-wheel side.

The leading feature of the design is the configuration of the body of the standard A, in open or half-column form, in a gracefully-rounded concavo-convex horizontal cross-sectional contour thereof, and in its easy tapering enlargement from the head toward the foot, where it joins the base B at one side, as represented in the drawings. The base B, in horizontal plane, is of approximately circular form, hollow within, and its exterior surface is concaved from a vertical line in a graceful curve from its upper beaded or molded front ledge, b, and the point of junction with the standard A at the back to the continuous base flange, c, of perceptibly larger diameter than across the ledge b. The base B, from the front or open side of the standard, thus presents the appearance of a horizontally-rounded and vertically concavo-convex basin, quite pleasing to the eye. Where the standard A joins the base B the standard assumes a semi-bulbous formation, which, combined with the continuous concavity of the base, presents an easy ogee outline. At the front molded edges, a, of the standard A, near the point of junction with the base, said front edges gradually recede in a graceful downward curve, d, thence continuing forward and downward along the inclined face of the journal-box seats or cen-

tral inclined joint of the journal-boxes, and merging into the horizontal ledge b at each side. At the inclined edges there are inwardly-projecting enlargements, on which the journal-boxes of the crank-shaft are placed, slanting downward toward the front and occupying a central position at each side of the base and standard at their point of junction. The head of the standard A is circularly flanged at e, to support the steam-cylinder, and beaded or molded edged brackets e', of easy vertical curvature, extend downward and backward from said flange, to merge with the front edges of the standard A at each side.

As thus far described, the standard and base are a complete distinctive design; but I may supplement the same with a portable foundation, of square form, as shown at C, having suitably-molded upper edges or corners, and an ornamental manufacturer's name-plate affixed thereto at the front.

A steam-engine standard and base thus designed are at once pleasing to the eye and suggestive of stability, and the ornamental effect is increased, rather than diminished, by securing the operative parts thereupon in correct alignment and in the full view that the configuration of the standard and base affords.

I claim—

1. The design for a steam-engine standard and base, consisting of the standard A, of a general open or half-column formation, connecting at one side with a base, B, of circular concavo-convex contour, substantially as shown and described. 80

2. In the design for a steam-engine standard and base herein shown and described, the rounded standard A, of enlarging taper from the head toward the foot, and of open or half-column configuration, and connecting at one side with a base, B, of circular concavo-convex outline, substantially as set forth. 85

3. In the design for a steam-engine standard and base herein shown and described, the standard A, of enlarging taper from the head toward the foot, and of open or half-column contour, and connected at one side with a base, B, of circular concavo-convex form, the front molded edges of the standard A connecting by easily-curved brackets e' with the circular 90

head flange *c*, and having the lower receding curvatures, *d*, merging into the inclined journal-box supports, and thence into the upper ledge, *b*, of the base *B*, having a lower flange, *c*, of larger diameter than the base and standard at the ledge *b*, substantially as set forth.

4. In the design for a steam-engine standard and base herein shown and described, the rounded standard *A*, of enlarging taper from head to foot, and of open or half-column formation, and the base *B*, of circular concavo-convex outline, connecting at one side with the standard *A*, having a semi-bulbous shape,

which connects with the concavity of the base in ogee configuration at the back, substantially as set forth. 15

5. In the design for a steam-engine standard and base herein shown and described, the tapering rounded open or half-column standard *A*, connecting at the back with the base *B* in 20 ogee vertical outline, as set forth.

ADAM ROSENKRANZ.
